Wilson M. Howard

UNITED STATES PATENT OFFICE

GEORGE BOULTON, OF ROCHESTER, NEW YORK, ASSIGNOR TO UNITED SHOE MACHINERY CORPORATION, OF PATERSON, NEW JERSEY, A CORPORATION OF NEW JERSEY

BLACKING MACHINE

Application filed December 8, 1927. Serial No. 238,656.

This invention relates to machines for applying a liquid such, for example, as ink, blacking or stain to the edges of sheet material and particularly to the edges of shoe 5 upper parts.

Work of this kind heretofore has been done with a hand brush and, consequently, has not been uniform in character nor carried out with any degree of certainty in all parts of 10 the edge treated; moreover, since the operator has been obliged at the same time to handle both the shoe part and an ink applying brush, the ink is bound to be smeared where it is not wanted and the whole operation is 15 troublesome both to the manufacturer and the operator.

An object of the present invention is to provide a machine by which liquid may be applied to the edges of sheet material rapidly, 20 accurately and uniformly and with a greater degree of cleanliness than heretofore. The invention further contemplates the provision of a machine adapted for handling all the 25 different shoe-upper parts which may be encountered in various styles of shoes, such as open and closed vamps and parts having edges of all shapes, including sharp curves or corners, and also the interior edges of cut-outs or perforations formed in the body of a 30 shoe upper.

An important feature of the invention consists in a novel ink applying tool, particularly adapted for inking the edges of a wide variety of shoe parts. As herein shown, the 35 tool has an elongated body portion with a roughened ink applying surface vertically disposed and with provision for supplying a continuous flow of ink upon its surface. It has been found that work having its edge 40 presented to, or fed in contact with, a tool of this character will exhibit the improved results sought. Ink is supplied to the surface of the tool by an enclosed screw conveyor, which pumps ink from a reservoir 45 through the interior of the tool and delivers it to its surface, where it is distributed by gravity flow. The tool may be run in continuous communication with the reservoir, when exterior edges are being treated, or it 50 may be lifted from the reservoir and run out

of communication therewith in applying its charge of ink to interior edges of cut-out portions in those cases where the tool must be passed through the shoe part.

I believe that a tool adapted for operation 55 in this manner has never before been available. Accordingly, another important feature of my invention consists broadly in a self-contained ink applying tool and pump organized to take up a charge of liquid and 60 then in its independent operation to circulate the contained charge in a continuous flow over the surface of the tool.

For handling closed uppers, it is desirable to have a cylindrical work support about all 65 sides of which the upper can be passed. With this consideration in view, another feature of the invention consists in an elongated ink reservoir arranged to extend from the frame free and clear of all obstructions, so that a 70 closed shoe part may be passed about all sides of the reservoir. As a further feature, and in order that the machine may be adapted to handle an assortment of stains and blackings with little delay in operation, the elongated ink reservoir is shaped to fit, in pre-determined position, in a socket in the frame 75 and to be detachably secured therein, so that it may be quickly and easily removed for cleaning and refilling or for substitution, 80 when desired.

The operation of the machine and the accurate and rapid presentation of work to the inking tool are greatly facilitated by means 85 of an improved gauge by means of which curling of the edge of the work is prevented and accurate gauging is, accordingly, facilitated.

To this end and in accordance with still another feature of the invention, the illustrated machine is provided with a gauge having opposed portions which are adjustable toward and from each other and are arranged to engage rather closely opposite sides of the work thereby to prevent curling of the edge. 90 As illustrated, the lower portion of the gauge is provided with an upward projection, the lateral surface of which serves as a gauge surface for contact with the edge of the work. 95 100

A resilient upper member secured to the lower member is adjustable toward and away from the lower member by means of a screw acting in opposition to a spring and is provided with an opening or recess to receive the gauge projection on the lower member.

These and other features of the invention will be best understood and appreciated from the following description of a preferred embodiment thereof, selected for purposes of illustration and shown in the accompanying drawings in which;

Fig. 1 is a view of the machine in side elevation, showing a portion of the bench in section;

Fig. 2 is a plan view of the front portion of the machine;

Fig. 3 is a view in perspective of the end of the reservoir with its associated gauge;

Fig. 4 is a view in elevation, on an enlarged scale, of the ink applying tool and its associated parts; and

Fig. 5 is a vertical section through the tool and the end of the ink reservoir.

The machine comprises a frame 12, from the rear side of which projects a shaft carrying an assembly of grooved pulleys 14, by which the machine is driven and from which its elements are operated, as will presently appear. The frame has a forwardly extending boss 16, provided with a socket for the reception of the elongated tubular ink reservoir 18, which serves also as a work support. This comprises a hollow, cylindrical member,

having a collar 20 with a pin, by which its longitudinal and angular position is determined with respect to the socket and the reservoir 18 is detachably secured in said socket by a clamping bolt 22. Adjacent to its rear end, the reservoir is provided with a short upstanding pipe 24 for filling purposes, and at its outer end it carries an idle work-supporting feed roll 26. A work gauge 27 to be later described is adjustably secured to the reservoir by a collar 28 and in the outer end of the reservoir is provided a restricted circular opening 29 (Fig. 3) in its upper surface through which an upright ink applying tool 30 passes in dipping into the ink contained in the reservoir, said tool nearly filling the opening.

The ink applying tool 30 has an elongated, hollow, rigid cylindrical body, terminating in a projection 32 of reduced diameter, having a tapering end. The body of the ink applying tool 30 has a lateral applying surface which extends vertically parallel to the axis of rotation and is provided with longitudinal grooves or flutes, alternating with ribs or lands. All of the flutes terminate at their upper ends in a circumferential groove 34 opening into which are a number of outlet ports 36 (Figs. 4 and 5). A spiral groove 37 is formed in the ribs of the body of the tool and a number of inlet ports 38 are located

near the lower end of the body. Inlet ports 39, connected by a spiral slot, are also provided in the lower projecting portion 32 of the tool.

Within the body of the tool 30 is located a screw conveyor 40, the thread of which fills the bore of the tool, leaving a space for liquid between the interior wall of the tool and the shank or shaft of the conveyor. It has at its lower end a portion 42 of reduced diameter which constitutes also a screw conveyor of small diameter and pitch and is located within the projecting end 32 of the tool.

In operation, the conveyor 40 is driven in a counter clockwise direction and the tool 30 in a clockwise direction, when viewed from above as indicated in Fig. 2. When the lower end of the tool is immersed in the ink in the reservoir 18, the ink flows in through the inlet ports 38 and 39 to the interior of the tool. It is then elevated or pumped up the passage in the tool by the screw conveyor and flows out through the outlet ports 36 to the groove 34, whence it flows by gravity down the roughened vertical applying surface of the tool, being distributed and retarded to some extent on its surface by the flutes and spiral groove thereon so that it may be dispensed to the edge of the work presented to it. In Fig. 4, a piece of work 100 is indicated as presented against the tool.

The screw conveyor 40 is formed on the lower end of a vertical shaft 44, journaled in a hollow concentric shaft 50 having a socket in its lower end for the reception of the tubular shank 31 of the tool 30. The hollow shaft 50 is journaled in vertical bearings formed in two branches of the front portion of the machine frame 12 and has pinned on its upper end a driving pulley 52 of relatively large diameter, by which the shaft is driven through a round belt 54 running over one of the grooved pulleys in the assembly 14.

The shaft 44 of the screw conveyor has pinned to it a pulley 46, disposed just above the pulley 52, and is driven by this through the crossed belt 47 in the opposite direction from the hollow shaft 50 and at a higher rate of speed. The shaft 44 is extended above its pulley 46 through a bracket 60, bolted to the top of the frame 12, and is provided at its upper end with a collar 48. The collar rests on a forked lever 62, pivotally mounted in ears of the bracket 60 and adjustably controlled in its position by an adjusting screw 64 threaded into the bracket. The adjusting screw 64, therefore, affords means for controlling the longitudinal relation of the screw conveyor 40 to the tool 30 and also with respect to the ink level in the reservoir while the interengagement of the pulley 46, set in position on the conveyor shaft 44 after the adjustment provided by the lever 62, with the hub of the pulley 52

maintains this relation regardless of the vertical position of the tool.

The hollow shaft 50 carries a collar 51 which rests on the outer end of a forked lever 53, pivotally mounted in the machine frame 12 and connected at its rear end to a treadle rod 55. By depressing the treadle rod 55, the hollow shaft 50 may be lifted with its tool 30 and in this movement the screw conveyor 40 is carried with the tool. The tool may thus be drawn clear of the ink reservoir 18 without disturbing the relation of the tool and conveyor and without interrupting the driving connections to either the tool or the screw conveyor, the belts 47 and 54 being led over idlers which permit the required displacement of the driven pulleys 46 and 52.

The frame 12 has two outwardly extending arms in which is slidably mounted a vertical tube 70, carrying a shaft 72 having a bevel gear 74 at its lower end. The bevel gear 74 meshes with another bevel gear 76 on the end of a short horizontal shaft, which carries at its inner end the upper driven feed roll 78 which cooperates with the idle feed roll 26 on the end of the ink reservoir 18. At its upper end, the shaft 72 carries a pinion 79 which is driven through an idle pinion 80 by a pinion 82 on the hollow shaft 50, located just below the pulley 52 which drives the latter. The tube 70 carries an inwardly projecting arm 84 which rests upon the collar 51 of the hollow shaft 50 so that, when the tool 30 is lifted, the upper feed roll 78 is also carried with it.

Adjustably mounted adjacent to the surface of the tool 30 is a flat vertical scraper 88, which is carried by a downwardly extending arm 89 secured to the frame and having a bearing for the tubular shank 31 of the ink applying tool. The scraper may be adjusted to remove surplus liquid from the tool 30 and has a pointed lower end so shaped as to direct such surplus liquid back to the lower portion of the tool and into the opening in the ink reservoir in spite of the fact that the tool nearly fills the opening.

An edge gauge, comprising a lower work supporting member 90 (Fig. 3) has an upwardly extending projection 92 which passes through an opening or recess in the upper member and the lateral surface of which acts as a gauge to contact with the edge of the work, frequently a flexible piece of thin leather such as is used for the upper of a shoe. This gauge is carried by and adjustably held by a set screw in the collar 28 which surrounds the ink reservoir 18. In order that the edge of the work may be held firmly in contact with the gauge projection 92, without danger of curling, there is also provided upon the gauge an upper member 94 which overlies and engages the upper margin of the work as the lower side is sup-

ported on the lower member 90. Since the upper member 94 is secured to the lower member 90 at a distance from the gauge projection 92, the upper member is slightly inclined with respect to the lower member and provides a tapered opening especially useful for work which has been skived or beveled. The ends of the gauge members are shaped to conform to the contour of the tool 30 and the upper member may be vertically adjusted in accordance with the thickness of the work by an adjusting screw 96 acting in opposition to the spring 97. The outer end of the upper member 94 is flared at 98 to facilitate insertion of the work.

The operation of the machine will be clear from the foregoing description but may be summarized briefly as follows: In treating exterior edges, the tool 30 occupies the position shown in Figs. 4 and 5 and the action of the screw conveyor 40 serves to suck up ink and to spill it on the applying surface of the tool and to maintain a uniform flow of ink upon this surface, this flow being adjustably controlled in quantity by the vertical adjustment of the screw conveyor and by the setting of the scraper 88. Work may be presented to the feed rolls and guided to the ink applying tool by the edge gauge. The effect of the spiral groove in the surface of the tool by its contact with the work is to cause the ink on its surface to be displaced upwardly, thus slowing its downward flow upon the tool surface and applying it thoroughly and rubbing it into the edge of the work.

When the interior edges of cut-outs are to be treated, the edge gauge is removed or slipped rearwardly on the ink reservoir. The tool having taken up a charge of ink from the reservoir is then elevated by the treadle so that its point may be passed through the cut-out portion and the work moved by hand to carry its edge across the surface of the tool. Where it is desired to treat the edges of narrow cut-outs or the corners thereof, the reduced projecting end 32 of the tool serves conveniently for applying the ink thereto, being designed to enter spaces too narrow to receive the body of the tool.

In its operation out of communication with the reservoir, the charge of ink is circulated and recirculated over the surface of the tool until exhausted by being dispensed to the work. This recirculation of the ink charge takes place because the ink flowing down the surface of the tool is taken in through the inlet ports 38 and 39, elevated by the screw conveyor 40 to the outlet ports 36 and discharged to the upper portion of the ink applying surface of the tool. What little ink fails to enter the inlet ports is directed by the tapered point of the projection 32 back to the center of the ink well.

It will be apparent that the machine de-

scribed herein and its various features are in no way limited to the handling of ink, but have general utility in the applying of any liquid to the edges of sheet material. It will be understood, therefore, that the term "ink" is used herein in an illustrative and not a restrictive sense.

Having thus described my invention, what I claim as new and desire to secure by Letters Patent is:—

1. An ink applying tool having an elongated ribbed body the ribs of which have a spiral groove formed therein.
2. An ink applying tool having an elongated ribbed body with intermediate ink-distributing flutes and having a reduced end portion, an ink-distributing spiral groove formed in the ribs of the tool, and a circumferential ink supplying groove communicating with said flutes.
3. An ink applying tool having a body with longitudinal vertically disposed flutes, a circumferential groove connecting the ends of the flutes and an outlet port leading to the groove.
4. An ink applying tool comprising an elongated hollow body having inlet and outlet ports and a roughened lateral surface for holding ink, together with an enclosed screw conveyor constructed and arranged to force ink through the outlet ports for delivery to said lateral surface.
5. An ink applying tool comprising an elongated cylindrical body terminating in a projecting portion of reduced diameter, the body of the tool being roughened for holding ink and having a supply opening whereby ink may flow by gravity upon the surface of the body and of the reduced projection.
6. A machine of the class described, having in combination an elongated, rigid, upright ink applying tool, means for maintaining a continuous and uniform flow of ink over the lateral surface of the tool, the surface of said tool being formed to retard the flow of ink thereover.
7. A machine of the class described, having in combination a hollow rotary tool having a vertically disposed ink applying surface, and means for elevating ink through the tool and delivering a continuous supply of ink to the upper portion of the tool to be distributed over its surface by gravity flow.
8. A machine for applying ink to shoe parts having, in combination, a rotatable substantially cylindrical elongated hollow tool having its peripheral surface disposed in upright relation in the machine, and means within said tool for collecting surplus ink at the lower end of the tool and delivering it to the periphery of the tool adjacent to its upper end.
9. A machine of the class described, having in combination a hollow rotary ink applying tool, and means located within the tool for moving a supply of ink to the lateral applying surface of the tool.
10. A machine of the class described having, in combination, an upright hollow rotatable ink applying tool with a lateral applying surface and having an inlet passage at its lower end and an outlet passage near its upper end, a screw conveyor located within the tool, and means for driving said screw conveyor to transfer ink from the lower passage to the upper passage, thereby to cause it to flow through said outlet passage over the applying surface.
11. A machine of the class described having, in combination, an ink reservoir, a self contained ink applying tool and pump arranged to run with one end dipping into the reservoir, said tool having a lateral applying surface whereby a continuous flow of ink is maintained from the reservoir down over the applying surface of the tool.
12. A machine of the class described having, in combination, an ink reservoir, a hollow rotary ink applying tool movable into the reservoir to receive a supply of ink and upwardly into a position out of communication with the reservoir to dispense its charge of ink.
13. A machine of the class described, having in combination an ink reservoir, and a self contained ink applying tool and pump movable into the reservoir to take a charge of ink and operating thereafter in a position removed from the reservoir to circulate the contained charge over the surface of the tool.
14. A machine of the class described, having in combination a frame, an elongated ink reservoir detachably secured therein and having an opening at its outer end, and a driven rotary ink applying tool mounted in the frame in alignment with the opening of the reservoir and movable into and out of said opening.
15. A machine of the class described, having in combination a frame having a socket, an elongated tubular ink reservoir having a lateral opening near one end and shaped to fit in predetermined position in the socket and to be detachably secured therein, and extending from the frame free and clear of all obstructions, whereby a closed shoe part may be passed about all sides of the reservoir, and an ink applying tool movably supported on the frame for movement into and out of said opening.
16. A machine of the class described, having in combination a work support, an elongated ink applying tool having a vertical ink applying face associated therewith, means for delivering ink to the upper portion of the tool to flow down over the applying face of the tool, a work gauge, and driven feed mechanism for sheet material acting to feed the work in a horizontal plane with its edge against the vertical surface of the tool.

17. A machine of the class described, having in combination a screw conveyor and an ink applying tool concentrically arranged one within the other, means for driving both of said members independently, interengaging means for adjusting and maintaining their longitudinal relation, and means for raising both the tool and the screw conveyor without disturbing their vertical relation. 70
18. A machine of the class described, having in combination an ink reservoir having a restricted opening, an elongated rigid tool rotatably mounted above and dipping in the reservoir and having a vertically disposed ink applying face, said tool nearly filling said opening, and a scraper located adjacent to the tool and tapered to return surplus ink by gravity to the opening of said reservoir. 75
19. A machine of the class described, having in combination a work support having an ink well provided with an opening in its upper surface, an ink applying tool dipping in the well through the opening and extending vertically above the work support, and an adjustable edge gauge mounted on the work support adjacent to the ink applying tool. 80
20. A machine of the class described, having in combination a frame, ink applying instrumentalities mounted for reciprocation thereon, and an elongated work support of relatively small cross section projecting from the frame free and clear of all obstructions, said work support containing an ink reservoir for supplying ink having an opening near its outer end to receive said ink applying instrumentalities as they are intermittently dipped therein. 85
21. A machine of the class described, having in combination a rotary tool having a vertically disposed lateral ink applying surface and an interior passage with a port opening through its lateral surface, and means for maintaining a flow of ink through the passage, outwardly through said port and over the applying surface. 90
22. A machine for applying ink to shoe parts comprising a reservoir, a tool having an elongated body portion dipping in the reservoir and a peripheral applying surface disposed in an upright position in the machine for the presentation of work thereto, said tool being constructed and arranged to suck ink from said reservoir and to spill it upon an upper portion of said peripheral surface to be distributed by gravity over the surface as the tool is applied to a piece of work. 95
23. A machine for applying ink to shoe parts having an applying tool with an elongated hollow body portion having a roughened peripheral applying surface disposed in an upright position in the machine, said tool having an outlet passage near its upper end and provided with means upon its peripheral surface to retard the flow of blacking down its applying surface, means for rotating said tool as pieces of work are presented to its peripheral surface, and means for elevating ink through said tool to spill it from said passage upon an upper portion of the periphery of the tool so that it can flow by gravity over the applying surface thereof. 100
24. A machine for applying ink to shoe parts having an ink applying tool with an elongated substantially cylindrical body portion adapted to be disposed in upright relation, means for rotating said tool on a vertical axis, the periphery of said body portion being provided with a spiral groove to conduct ink over the peripheral surface thereof. 105
25. A machine for applying ink to shoe parts comprising an upright tool having an elongated body portion adapted to have its periphery covered with ink for application to the work, and means for collecting surplus ink near the lower end of the tool and delivering it to an upper portion of the tool so that it will again flow down over the peripheral surface thereof. 110
26. A machine for applying ink to shoe parts comprising an ink reservoir, a hollow applying tool movable into and out of said reservoir, and means associated with said tool constructed and arranged to fill said hollow tool with ink while it is in the reservoir and to circulate the ink over the surface of the tool while the tool is out of the reservoir. 115
27. In a fluid-applying machine, a fluid-applying member, and a gauge associated with the member and having superposed end portions relatively adjustable toward and from each other, said portions being arranged to engage overlying margins of the work. 120
28. In a fluid-applying machine, a fluid-applying member, and a gauge associated with the member and having a fixed portion and a portion adjustable toward and from the fixed portion, said portions being arranged to engage opposite sides of the work and one being inclined with respect to the other. 125
29. In a fluid-applying machine, a fluid-applying member, a gauge associated with the member and having a fixed portion and a portion adjustable toward and from the fixed portion, a spring forcing one portion toward the other, and a screw threaded through one portion and contacting with the other. 130
30. In a fluid-applying machine, a fluid-applying member, and a gauge having relatively movable portions arranged for contact with opposite sides of the work, there being a projection upon one portion arranged for contact with the edge of said work. 135
31. In a fluid-applying machine, a fluid-applying member, and a gauge having relatively movable portions arranged for contact with opposite sides of the work, there being a projection upon one portion arranged for contact with the edge of said work and an 140

opening in the other portion to receive the projection.

32. In a fluid-applying machine, a fluid-applying member, and a gauge having relatively movable portions arranged for contact with opposite sides of the work, there being a projection upon one portion arranged for contact with the edge of said work and the said portions having work-engaging surfaces diverging from the projection.

10 33. In a fluid-applying machine, a member arranged for engagement with the work, a support for said member, a carrier adjustable upon the support toward and from the work-engaging member, and a gauge having a portion fixed upon the carrier and a portion movable upon the carrier toward and from the fixed portion.

15 34. In a fluid-applying machine, a fluid-applying member, and a gauge having a work supporting portion provided with an upwardly extending projection, the lateral surface of which serves as a gauging member for contact with the edge of the work, said gauge being provided with an upper portion having a recess to receive said projection and a screw for adjusting the relation of the upper and lower members.

20 35. A machine of the class described having, in combination, a work support, a rotary tool having an upright ink-applying face, means for delivering ink to flow down over the applying face of the tool, means for retarding the downward flow of ink, a work gauge, and driven feed mechanism constructed and arranged to feed sheet material in a horizontal plane with its edge guided by said gauge past the upright surface of the tool to coat the edge of the work.

25 36. In a fluid applying machine, a fluid applying member, and a gauge for sheet material associated with the member and having end portions relatively adjustable toward and from each other, one of which guides the work and supports a margin thereof and the other of which is arranged to overlap the superposed opposite marginal portion of the work.

30 37. In a fluid applying machine, a support, a work supporting member carried thereby, a gauge carrier adjustably mounted on said support for movement toward and from the work supporting member, and a gauge on said carrier having relatively movable members adapted to engage superposed margins of a piece of work, one of said members having a work guiding projection and said gauge having screw and spring means for relatively adjusting said members.

35 In testimony whereof I have signed my name to this specification.

GEORGE BOULTON.
